ABSTRACT OF THE DISCLOSURE

A keying circuit for a monophonic keyboard instrument consisting of a series of sequentially connected double-throw switches. In response to playing of any key, a percussive modulating signal is applied to the tone signal being played. In this way percussive tones may be generated without requiring additional switches or switch contacts over and above the normal keying contacts already present.

This invention relates to percussion circuits for a monophonic musical instrument, or the monophonic portion of a polyphonic musical instrument. Specifically, the invention will be described with reference to a percussion circuit for the pedal clavier of an electronic organ.

It is an object of this invention to provide a simplified and economical percussion circuit for the pedal clavier of an electronic organ.

It is a further object of this invention to provide such a percussion circuit which does not require any additional switches or contacts, but operates from the actuation of the already existing pedal clavier switching.

In accordance with these and other objects which will become apparent hereinafter, preferred forms of the invention will be now described with reference to the accompanying drawings wherein:

FIGURE 1 is a circuit diagram of one form of the present invention, and

FIGURE 2 is a circuit diagram of a second form of the invention.

Referring to FIGURE 1, 11 designates a sequence of single pole, double-throw switches connected in monophonic sequence. That is, only one tone (a pedal tone) will be sounded by the organ at any one time, irrespective of how many pedal keys may be depressed. When a plurality of keys are depressed simultaneously, only the lowest pitch will sound.

Each double-throw switch of the switch sequence 11 consists of a pole 12, a normally-closed contact 13, and a normally-open contact 14. Each pole 12 is linked to a pedal key 15, which when actuated or played by the foot of the organist, moves the pole 12 from the normally-closed contact 13 to the normally-open contact 14. When the pedal key is released, the pole 12 is biased into contact with the normally-closed contact 13. The normally-closed contact 13 of each switch 11 is connected to the pole 12 of the next higher switch in the sequence, as shown by the representative connection 16.

In the multi-conductor cable 20 are a plurality of individual conductors, each carrying a respective tone signal from a tone signal generator or source, to successive normally-open contacts 14. The normally-open contact 14 of the first switch in the sequence receives the lowest pitched of the tone generator sources, in this case shown as C2, while the last or upper-key switch in the sequence 11 receives the highest tone, in this case C3. Thus, in the example shown, there are 13 key switches in the sequence 11, spanning a complete octave in the chromatic scale.

The pole 12 of the first switch in the sequence is connected through a resistor 17 to an intermediate output

circuit, in this case a pedal divider 18. The pedal divider serves to cut the tone frequency in half, so that a tone one octave below that applied to its input appears at its output 19.

The circuit thus far described constitutes the foundation to which the present invention is applied. Its operation is well known and is substantially as follows:

The tone signal in the form of rectangular pulses of given frequency resides on successive normally-open contacts 14, as represented by the wave form 21. Whenever a pedal key is actuated, the tone signal applied to that particular key switch 11 goes through the pole 12, resistor 17, pedal divider 18, and to the output 19. Since higher pitch tones must pass through the poles 12 of each switch of lower pitch, it follows that the actuation of any key switch of lower pitch will preempt the circuit. Thus, should several pedal keys be depressed simultaneously, only one tone signal, of the lowest pitch, will appear at the point 27 and be applied to the pedal divider 18.

In accordance with the present invention, the normally-closed contact 13 of the last or highest switch in the sequence is employed as a take-off point for a percussion pulse which generates a percussive envelope, so that a percussed burst of pedal tone signal may be applied to the final output system whenever any pedal key is depressed.

Normally, this last contact 13 is unused, but in accordance with the present invention, it is connected by means of a conductor 23 through a resistor 24 to a source of negative voltage 26. The conductor 23 also connects to point 31, which represents the control terminal of a percussion circuit 32. Also in accordance with the present invention, the terminal 27 connected to the first pole 12 is grounded at 43 through a diode 28 poled as shown. These elements cause a negative going step voltage 29 to appear at 31, whenever a pole 12 is actuated.

Step 29 institutes charging of a capacitor 30, causing a negative sawtooth 33 to appear on the other side 56 of the capacitor 30. This is applied through resistors 34 and 36 to one terminal 37 of a diode 38. The terminal 37 constitutes an input terminal for the percussion circuit 32, to which the conductor 19 applies the output signal 39 of the pedal divider 18. Normally, the diode 38 is reversed biased, so that tone signal 39 will not pass therethrough to the point 51 and thence to the pedal volume potentiometer 41. The appearance of the negative sawtooth 33 on the terminal 37 allows the signal 39 to pass through the diode 38 in decreasing amplitude as the sawtooth 33 rises. There is thus applied to the output 42 of the percussion circuit 32 a percussed burst of pedal tone 39 having an envelope shape in accordance with the pulsing sawtooth 33.

Block 58 represents a final output system of any suitable form which ultimately usually contains some form of electro acoustic transducer represented by the loudspeaker 59.

Operation of the circuit of FIGURE 1 will now be reviewed in detail.

Normally, i.e. when none of the switches 11 is operated, the input terminal 37 is held substantially at ground potential by the ground 43 through the diode 28. There is, of course, a small flow of circulating current through the resistor 24 and diode 28 by virtue of the negative bias 26. Likewise, the points 37 and 56 are at ground potential by virtue of the ground connection 44. Since both sides of the capacitor 30 are substantially at ground potential, the capacitor is uncharged.

When any one of the switches 11 is operated so that its pole 12 leaves its normally-closed contact 13, the capacitor 30 begins to charge from the negative voltage source 26 through the resistors 24, 46, 34, 36, and circuit 18. Charging current also flows in resistor 47. The charg-

ing current produces the sawtooth 33; as the charging current decreases, the potential 33 appearing at the terminal 37 rises to resume ground potential. The function of capacitor 40 is to round off the initial down step in the sawtooth 33, at the point 45.

Actuation of a switch 11, in addition to producing the step voltage 29 at the terminal 31, also applies tone signal from the corresponding tone signal source connected to the cable 20, through the resistor 17 and pedal divider 18, to the input terminal 37 of the percussion circuit 32. Since this signal is of positive polarity, as shown at 39, the diode 38 constitutes a modulator or gate which blocks passage of tone signal 39 unless the diode is forward biased a sufficient amount to let the signals 39 pass. Such a bias is provided by the voltage 33, the magnitude of which is sufficient to unblock the gate formed by the diode 38. This passes tone signal 39 through to the terminal 51, thence through the coupling capacitor 52, to the slider of the pedal volume potentiometer 41. Resistors 53 and 54 and capacitors 50 and 50' constitute voicing elements for the percussed tones. Resistor 54' forms a return path for direct current flowing through diode 38.

As the terminal 56 of the capacitor 30 returns to ground potential, the amplitude of the tone signal 39 is steadily cut down by the loss of forward bias across the diode 38. Thus, the wave form 33 constitutes in effect a modulating signal which permits passage of a percussed burst of pedal tone 39 to the output circuit 58.

The connection between the point 27 and ground 43 has been shown as a diode 28 and this is the preferred circuit element. However, the essential characteristic of this element is that it be of low impedance relative to that of the element (resistor) 24, with which it forms a voltage divider across the negative source of voltage 26 at least insofar as voltage poled as shown is concerned. If a resistance were to be substituted at 28 having a value relatively low with respect to the value of resistor 24, the same phenomenon would be experienced but with less efficiency. In such a case there would be a small current constantly flowing through the element 28, switch sequence 11, and resistor 24, which would place the point 27 at a potential somewhat below ground, the extent being determined by the voltage division between 24 and 28. Upon actuation of any of the switches 11, the terminal 31 would drop to a more negative potential, as shown by the wave form 29. The principal difference in operation would be the starting point for the step function 29; in the case of the diode, it would start appreciably closer to ground than in the case of a bilaterally-conducting element such as a resistor at 28. Employment of a diode as the element 28 permits virtually complete functional isolation of the pedal divider input from the input of the percussion circuit 32. The tone signals appearing in the switches 11 have one polarity (positive) and go to the pedal divider, being isolated from the percussion circuit 32 by the opening of a normally-closed contact 13. The signal 29 for driving the percussion circuit 32 is of the opposite polarity (negative) and is allowed to complete its circuit through the diode 28, without affecting the tone signals. To the positive going tone signal at the point 27, the diode is virtually an open circuit and can be functionally ignored. To the negative going percussion signal 29, the diode is virtually a short circuit, thus permitting virtually all of the voltage 29 to be developed at the terminal 31.

In the usual operation, the pedal switch 11 will be held down by the organist for a time longer than the normal percussive time span of the wave form 33, so that the circuit will operate usually as described above. In case the organist wishes to inject a staccato effect even shorter than the percussive time of circuit 32, he raises his foot from the pedal operating the switch 11 even before the percussive envelope represented by 33 has terminated. In this event tone signal at the output 42 terminates abruptly for either of two reasons.

In the first place, release of the switch 11 opens the

contact 14, thereby isolating the pedal divider 18 from its source of tone signals in cable 20. In the second place, return of the pole 12 to the normally-closed contact 13 immediately grounds the control terminal 31 through the diode 28 to the ground point 43. Since the point 31 had previously been negative, this reflects as a positive going step voltage at the point 31, which manifests itself in turn as a positive pulse at the point 56. This discharges the capacitor 30 through the diode 57. The gate diode 38 immediately in effect becomes reversed biased and blocks any further passage of signals from point 37 to point 51, even if such signals were still appearing on the input 19.

A second form of the invention, illustrated in FIGURE 2, has the characteristic that the tone signal is not so abruptly terminated as described immediately above, even should the organist release the key prior to culmination of the normal percussive envelope. The circuit of FIGURE 2 illustrates the adaptation of the present invention to a more sophisticated and refined keying circuit.

In the circuit of FIGURE 2, parts corresponding to those found in FIGURE 1 have been designated with the same numeral followed by a suffix *a*.

The normally-open contact 14a of each of the switches 11a in the sequence controls a respective tone signal from the cable 20a. The control connection is through a circuit which includes a back or reverse biased diode 65 and a resistor 66. The diode 65 constitutes a gate which prevents tone signals 21 from passing to the output line 67 (through the individual coupling capacitors 68), except when the diode 65 is forwardly biased by the actuation of a respective pole 12a. When this is done, positive bias from a voltage source 69 is applied through a resistor 71 to the terminal 27a of the first pole 12a in the switch sequence 11a. The switches 11a are connected sequentially in the same manner as in FIGURE 1, so that each switch 11a has constantly applied to its pole 12a the positive bias 69, unless one or more of the switches lower on the keyboard has been moved to actuated position. Thus, only the lowermost pitch actuated at any one time will be sounded, the same as in the FIGURE 1 circuit.

Application of the positive bias from 69 to the point 72 applies a forward bias to the diode 65, allowing the rectangular wave tone signal 21 to appear at the point 72, and be applied through the capacitor 68 and line 67 to the input of the pedal divider 18a. As in the circuit of FIGURE 1, this signal is divided in frequency and appears as shown at 39a at the point 19a, where it encounters the back biased diode 38a.

A percussed burst of signal is allowed to pass through the diode 38a by the application thereto of a sawtooth gating pulse 33a. This substantially is the same as the pulse 33 of FIGURE 1, except it is positive instead of negative, and, hence, is applied to the opposite pole of the diode 38.

The sawtooth 33a is the result of a positive going step voltage 29a applied to the point 31a by the actuation of any one of the poles 12a. Upon operation of any switch 11a, a charging current flows from the source 69, through the pole 12a, isolating diode 73, and thence to the terminal 31a, capacitor 30a, diode 77, resistor 78, diode 38a and circuit 18a. Charging current also flows through resistor 74 to ground connection 76. Since the resistance 74 is much larger than the resistance 71, substantially the full voltage from the source 69 is promptly felt on the terminal 31a. As the capacitor 30a charges up, the voltage at 56a gradually drops back to ground potential, as shown at 33a.

The sawtooth voltage 33a passes without substantial attenuation through the diode 77 and resistor 78 to the point 79, where it serves to forwardly bias the diode 38a and allow the signal 39a to reach the point 79. From there the tone signal 39a passes through the coupling capacitor 81 to the output terminal 42a. Resistors 82 and 83 and capacitor 80 constitute a voicing network for the percussed tone signals.

The function thus far described for FIGURE 2 is substantially the same as the function of the corresponding parts in FIGURE 1. The chief difference in function between the circuits of FIGURE 2 and FIGURE 1 occurs in case the organist releases the actuated pole 12a before the percussion pulse or envelope 33a has run its full course. In such an event, the FIGURE 2 circuit produces a slight tone sustain, which to most ears is more pleasing than the abrupt termination produced by FIGURE 1.

The circuit of FIGURE 2 is employed in an organ having an appreciable sustain to the tone after the release of a key. The organ also has a feature which prematurely terminates the sustain should a second key be played before the sustained tone has run its course. Such features are disclosed in co-pending application, Ser. No. 378,117, filed June 26, 1964, now abandoned and the continuation-in-part thereof Ser. No. 701,032, filed Jan. 4, 1968.

The persistence of the tone signal 39a at the point 19a, after departure of a pole 12a from contact 14a, is due to the pedal sustain feature embodied in FIGURE 2. This is effected by storage of gate opening potential on respective capacitors 86, which contain a residual charge that maintains the operated gate 65 open long enough to sustain the tones at 19a for a predetermined period.

Since the tone is available at 19a, it is desirable to cause it to taper off somewhat less abruptly than would be the case if the gate 38a were to be closed abruptly by removal of the forward bias from point 79. This is effectuated by the storage of a charge on the relatively-small capacitor 87. The abrupt termination of the positive sawtooth 33a appearing at the point 56a is not reflected on to the capacitor 87 because of the presence of the isolating diode 77. Thus, the termination of the sawtooth 33a simply causes the diode 77 to appear substantially as an open circuit to the capacitor 87, which then proceeds to discharge through the resistor 78, diode 38a, and the circuitry of the pedal divider 18a. This discharge is relatively rapid and produces a very short tail. It is, however, less abrupt than the cutting off which would otherwise occur, and produces for many purposes a more desirable tonal effect.

Closing of switch 94 grounds point 79 and disables the percussion circuit completely.

As alluded to hereinbefore, the circuit of FIGURE 2 involves certain pedal sustain and pedal cancel circuitry illustrated schematically in part by the block 89. Such circuitry also feeds to the ultimate output circuit represented schematically at 91, which includes some form of electro acoustic transducer such as loudspeaker 92.

It is to be understood that in both FIGURE 1 and FIGURE 2 the tone signal sources which feed the cable 20 are ultimately returned, at least insofar as tone signal frequencies are concerned, to the same ground as illustrated in these figures; and that the bias voltages referred to herein have reference to that same ground potential.

It will be readily seen also that the pedal divider is not necessary to the functioning of the present invention. If desired, the invention herein could be employed without the pedal divider simply by passing the same frequency from the cable 20 directly to the diode 38 without dividing the frequency.

While the instant invention has been shown and described herein in what is conceived to be the most practical and preferred embodiments, it is recognized that departures may be made therefrom within the scope of the invention which is, therefore, not to be limited to the details disclosed herein but is to be afforded the full scope of the invention as hereinafter claimed.

What is claimed is:

1. A keying circuit for a monophonic electronic musical instrument, comprising:
a sequence of double-throw switches, each having a pole, a normally-closed contact, and a normally-

open contact; a plurality of playing keys, one for each said switch, and linked to a respective pole thereof, each said pole residing on the normally-closed contact, except when the corresponding key is in actuated position;

a plurality of different tone signal sources;

an intermediate output system;

a plurality of first-circuit means each connected between a normally-open contact of a switch and a respective tone signal source and effective to apply a tone signal to said intermediate output system whenever the corresponding key is actuated so as to move the pole from the normally-closed to the normally-open contact;

the normally-closed contact of each switch being sequentially connected to the next succeeding switch in the sequence, except for the last switch in the sequence;

second circuit means connected to the pole of the first switch in said sequence for electrically returning said last-named pole to said plurality of tone signal sources;

step-function circuit means for generating a step-function signal in response to actuation of any of said switches from its normally-closed to its normally-open contact;

a final output system;

percussive envelope means for applying tone signals from said intermediate output system to said final output system;

said step-function circuit means being connected to said percussive envelope means for causing said percussive envelope means to pass a percussed burst of tone signal from said intermediate output system to said final output system in response to each application of a step-function signal.

2. In a keying circuit for a monophonic electronic musical instrument having a sequence of double-throw switches, each having a pole, a normally-closed contact and a normally-open contact; a plurality of keys corresponding to said switches and connected respectively thereto, each key when actuated serving to move the pole of the corresponding switch from the normally-closed to the normally-open contact; a plurality of different tone signal sources corresponding to said switches, each having its output connected to the normally-open contact of the corresponding switch; the normally-closed contact of each switch except the last in the sequence being sequentially connected to the pole of the next succeeding switch in the sequence; an intermediate output system connected to the pole of the first switch in the sequence, whereby upon actuation of any key, the tone signal from its corresponding tone signal source is applied to said intermediate output system, the improvement comprising:
a percussion circuit including:

an input connected to the output of said intermediate output system, an output adapted to be connected to a final output system, and a control terminal connected to the normally-closed contact of the last switch in said sequence;

a source of bias potential connected between said control terminal and said pole of said first switch in the sequence;

diode means connected in series with and between said source of potential and said pole of said first switch;

gating means for passing tone signals from the input to the output of said percussion circuit in response to existence of an input pulse on said gating means;

pulse-shaping means responsive to voltage change appearing on said control terminal for applying a percussion envelope pulse to said gating means, thereby to pass a burst of percussed tone signal

from the input to the output of said percussion circuit.

3. In a keying circuit for a monophonic electronic musical instrument having a sequence of double-throw switches, each having a pole, a normally-closed contact and a normally-open contact; a plurality of keys corresponding to said switches and connected respectively thereto, each key when actuated serving to move the pole of the corresponding switch from the normally-closed to the normally-open contact; a plurality of different tone signal sources corresponding to said switches, each having its output connected to the normally-open contact of the corresponding switch; the normally-closed contact of each switch except the last in the sequence being sequentially connected to the pole of the next succeeding switch in the sequence; an intermediate output system connected to the pole of the first switch in the sequence, whereby upon actuation of any key, tone signal from its corresponding tone signal source is applied to said intermediate output system, the improvement comprising:

a percussion circuit including:

an input connected to the output of said intermediate output system, an output adapted to be connected to a final output system, and a control terminal connected to the normally-closed contact of the last switch in said sequence;

a source of bias potential connected between said control terminal and said pole of said first switch in the sequence;

first impedance means connected in series with and between said source of potential and said control terminal;

second impedance means connected in series with and between said pole of said first switch and the other side of said source of potential, said second impedance means appearing at least to a voltage of given polarity as a low impedance relative to said first impedance means;

gating means for passing tone signals from the input to the output of said percussion circuit in response to existence of an input pulse on said gating means;

pulse-shaping means responsive to voltage change appearing on said control terminal for applying a percussion envelope pulse to said gating

5

means, thereby to pass a burst of percussed tone signal from the input to the output of said percussion circuit.

4. A keying circuit for a monophonic electronic musical instrument, comprising:

a sequence of double-throw switches, each having a pole, a normally-closed contact, and a normally-open contact; a plurality of playing keys, one for each said switch, and linked to a respective pole thereof, each said pole residing on the normally-closed contact, except when the corresponding key is in actuated position;

a plurality of different tone signal sources; an intermediate output system;

a plurality of first-circuit means each connected between a normally-open circuit of a switch and a respective tone signal source and effective to apply a tone signal to said intermediate output system whenever the corresponding key is actuated so as to move the pole from the normally-closed to the normally-open contact;

the normally-closed contact of each switch being sequentially connected to the next succeeding switch in the sequence, except for the last switch in the sequence;

triggering circuit means for generating a triggering signal in response to actuation of any of said switches from its normally-closed to its normally-open contact; a final output system;

modulator means for applying tone signals from said intermediate output system to said final output system;

said triggering circuit means being connected to said modulator means for causing said modulator means to pass a percussed burst of tone signal from said intermediate output system to said final output system in response to each application of a triggering signal.
